United States Patent Office.

LOUIS HILLEBRAND, OF PHILADELPHIA, PENNSYLVANIA.

Design No. 2,966, dated March 31, 1868.

DESIGN FOR A KEY-SOCKET.

The Schedule referred to in these Letters Patent and making part of the same.

TO ALL WHOM IT MAY CONCERN:

Be it known that I, LOUIS HILLEBRAND, of the city and county of Philadelphia, and State of Pennsylvania, have invented a new and useful Design for Key-Sockets; and I do hereby declare the following to be a clear and exact description of the nature thereof, sufficient to enable others skilled in the art to which my invention appertains to fully understand and use the same, reference being had to the accompanying drawings, making part of this specification, in which—

Figure 1 is a front view of the design illustrating my invention.

Figure 2 is a side view thereof.

Similar letters of reference indicate corresponding parts in the two figures.

My invention consists of a neat and useful design for the socket which receives the key of a lock, as will be hereinafter more fully described.

In the drawings, A represents a portion of a lock-plate of ordinary form and construction, and having a slot, *a b*, for receiving the bits and shank or spindle of the key which enters the lock. On a portion of the plate surrounding the slot, I secure a six-pointed star, B, which lies flat on the plate, and is made of any suitable metal or material. A slot similar to the slot *a b* is formed in the body and points of the star. On the star I place a socket, C, which may be said to be formed of two similar vertical sections of a truncated cone, each section being arranged on opposite points of the side edges of the slot *a b*, and having on its inner face a groove, *d*, so as to correspond in shape with the portion *b* of the slot *a b*, which it surrounds.

A neat and useful design is produced, which may be applied to various kinds of locks, as desired.

Having thus described my invention, what I claim as new, and desire to secure by Letters Patent, is—

The design for key-sockets, substantially as described, and represented in the drawings.

To the above, I have signed my name, this 2d day of March, 1868.

L. HILLEBRAND.
